BUTTON

John A. Devendor and William A. Devendor,
Jackson Heights, N. Y.

Application January 8, 1934, Serial No. 705,720

11 Claims. (Cl. 24—96)

This invention relates to buttons and more particularly to buttons of the class adapted to be quickly and economically applied to wearing apparel, either for ornamental or utilitarian purposes, or both.

It is an object of the invention to effect improvements in buttons which may be quickly and inexpensively applied to fabric by a simple clinching operation. Buttons of this general character in the past have included a collet portion having an upturned marginal flange and having prongs struck from the intermediate portion of the body and extending downward therefrom. There is necessarily a limitation imposed upon the length of prong which can be secured with a construction of this kind since the prongs, if struck from radially extending sectors, must terminate short of the center of the collet. Where the prongs are struck from the collet body, moreover, a gap is formed in the body portion of the collet so that it is impossible to provide a clinching or clamping surface to coact with the inturned prongs in gripping the fabric to which the button is attached.

In accordance with the present invention, provision is made of a button body and a collet fitting therein, the collet being provided with a downturned flange and having prongs extending downward from the free edge of the flange. Since the prong material in this kind of construction is not taken from the collet body there is no limitation upon the length of prong which may be employed, and prongs of suitable length for use even where the button is to be applied to thick fabric may readily be provided. The body portion of the collet, moreover, is not perforated by the formation of the prongs, and hence it is possible for the fabric to which the button is applied to be firmly gripped between the inturned prongs and the collet body.

A further desirable feature of one form of embodiment of the invention relates to the formation of the collet with a downwardly convex body portion. The body portion thus presents a lower surface for coaction with the inturned prongs which may lie in contact with the normal plane of the fabric to which the button is attached, or so close thereto that no substantial distortion of the fabric is involved when the inturned prongs are pressed upward toward the button body. It is a further point with reference to this construction that the button attaching pressure which is applied to the collet body when the prong tips are pressed upward has no tendency to cause the collet flange to release its grip

upon the cover fabric which is clamped between the collet flange and the body. On the contrary, any distortion which might occur would have exactly the opposite effect and tend to urge the collet flange outward into firmer gripping relation.

The formation of the prongs upon the collet as described also makes possible the provision of other novel forms of buttons which present attractive and pleasing ornamental effects.

Other objects and advantages will hereinafter appear.

In the drawing forming part of this specification and illustrating certain preferred embodiments thereof:

Figure 1 is a bottom plan view of a button embodying features of the invention;

Figure 2 is a vertical sectional view of the button of Figure 1 taken on the section line 2—2 of Figure 1, looking in the direction of the arrows;

Figure 3 is a plan view, partly broken away, illustrating another form of button embodying features of the invention;

Figure 4 is a vertical sectional view taken on the line 4—4 of Figure 3, looking in the direction of the arrows;

Figure 5 is a plan view illustrating a further embodiment of the invention;

Figure 6 is a vertical sectional view taken on the section line 6—6 of Figure 5, looking in the direction of the arrows;

Figure 7 is a plan view of a still further form of button embodying features of the invention; and

Figure 8 is a vertical sectional view taken on the section line 8—8 of Figure 7, looking in the direction of the arrows.

In the embodiment of Figures 1 and 2, the button comprises a body member 1 having a downturned marginal flange 2. A fabric cover 3 extends over the top of the body member, down around the marginal flange, and up into the hollow body. The marginal portion of the cover fabric is gripped to the body by a downturned flange 4 provided upon a collet 5 which fits within the body. The collet 5 is provided with downwardly extending prongs 6 which, it will be observed, are formed from material external to the collet flange 4 and which, therefore, may be made of any length desired.

The lower tip portions 7 of the prongs 6 are turned in slightly to facilitate the bending inward of the prongs when the prongs are driven against an anvil in the operation of attaching the button to a garment or other fabric.

The body portion 8 of the collet which lies within the marginal flange 4 is displaced downward and desirably presents a downwardly convex lower surface. The lowermost portion of this surface is shown as substantially in the plane of the lower edge of the collet flange, but it may be displaced downward to a greater or lesser extent as desired. The downwardly displaced portion of the collet body provides surfaces in radial alignment with the prongs and closely adjacent to the fabric to which the button is attached, against which the prongs may be clamped or clinched. The button is thus firmly and immovably held to the garment or other fabric to which it is applied and strain upon the fabric at the holes pierced by the prongs is avoided.

When the downwardly displaced portion of the collet body is made convex as shown the pressure exerted by the prong clinching anvil can have no tendency to contract the collet and cause release of the cover material.

While the button is susceptible of many uses, one important use is the attachment of it to caps at the point where all of the panels of the cap come together. In such a location the numerous pieces coming together form a bunch or knot and the fabric is quite thick so that the long prongs affording firm securement of the prongs to the fabric is very desirable. The fact that the prongs grip against the lower face of the collet body is very useful in this connection also, since the cap panels are narrow at their point of union and it is desirable to avoid strain at the openings in the fabric formed by the piercing action of the prongs.

The embodiment of Figures 3 and 4 is generally similar to that of Figures 1 and 2. This embodiment differs from that of Figures 1 and 2, however, in that the body 1a is provided with a central opening 9 through which the top surface of the collet may be seen. Where this construction is used the collet body 8a is desirably flat and may be enameled or otherwise ornamented so that a pleasing combination is presented to view. The collet body is not required to be perforated, and may therefore be caused to present a smooth, unbroken surface to view. The cover fabric 3a has the inner marginal portion thereof gripped between the body member 1a and the collet body 8a, and the outer marginal portion thereof gripped between the downturned flanges of the body and collet, 2a and 4a. As before, the collet is provided with downturned prongs 6a.

In this instance no downwardly convex gripping surface is provided for coacting with the prongs, but this feature is not necessary for all purposes to which the button may be put. The body of the collet desirably lies in juxtaposed relation to the body member, so that it grips the inner margin of the cover fabric securely. Such a construction is readily provided in conjunction with the provision of the pronged, downturned flange, since it involves no displacement of the collet body from the normal plane thereof.

In the embodiment of Figures 5 and 6 the body 1b is also perforated, and it is provided with a downturned inner flange 10 as well as a downturned outer flange 2b. The cover fabric 3b has its inner marginal portion extended downward around the inner flange 10 and between the collet body 8b and the lower face of the top of the body member 1b. The outer margin of the cover fabric is gripped between the body flange 2b and the downturned collet flange 4b as before. When this embodiment is employed, a portion of the

fabric to which the button is attached shows through the central opening of the button. The downturned collet flange 4b has prongs 6b extending downward from the free margin thereof, as in the other embodiments described. In this embodiment the prongs may be clinched or clamped against the downturned flange 10 of the body 1b.

In the embodiment of Figures 7 and 8, a body portion 8c of the collet 5c is provided with a raised central portion 11 which is surrounded by an annular, downwardly convex portion 12. A piece of covering fabric 13 extends over the collet and down around the downturned flange 2c thereof. The body member 1c is an annular member which extends downward at its margin into the annular groove or valley formed in the upper face of the collet body 8c. A piece of cover fabric 3c has its inner margin received between the inner, lower face of the body member 1c. This fabric extends outward and downward around the flange 2c of the body 1c and thence upward between the flanges 2c and 4c of the body and the collet. The outer margins of both the cover fabric pieces 13 and 3c are clamped between the flanges 2c and 4c. Prongs 6c extend downward from the free edge of the downturned flange 4c of the collet. When the button is applied to a piece of fabric the prongs, after penetrating the fabric, may be turned upward and clinched or clamped against the lower convex face of the annular portion 12 of the collet.

While we have illustrated and described in detail certain preferred forms of our invention, it is to be understood that changes may be made therein and the invention embodied in other structures. We do not, therefore, desire to limit ourselves to the specific constructions illustrated, but intend to cover our invention broadly in whatever form its principle may be utilized.

We claim:

1. In a button, in combination, a hollow body having an inner body portion and a downturned peripheral flange, a collet therein, said collet substantially fitting the body and bearing against the inner body portion thereof and having a downturned marginal flange fitting within the body flange and attaching prongs extending downward from the marginal flange, and a piece of fabric covering the body and having the marginal portion thereof gripped between the body and collet flanges.

2. In a button, in combination, a hollow body and a collet therein, said collet having a downturned marginal flange fitting within the body and attaching prongs extending downward from the marginal flange, the intermediate portion of the collet lying within the flange having a downwardly projecting boss adapted to coact with the clinched prongs in clinching the material to which the button is applied.

3. In a button, in combination, a downwardly concave hollow body having a downturned peripheral flange, and a collet therein, said collet having a downturned marginal flange fitting within the peripheral flange of the body and attaching prongs extending downwardly from the marginal flange, the tips of the prongs being slightly inturned to facilitate inward clinching of the prongs.

4. In a button, in combination, a body member having a downturned marginal flange, a collet member within the body also having a downturned marginal flange, and a fabric cover for the body member having marginal portions there-

of gripped between the body and collet flanges, said collet having attaching prongs extending downward from the marginal flange thereof and having a portion within the collet displaced downward and providing a downwardly convex surface for coacting with the prongs.

5. In a button, in combination, a body member having a downturned marginal flange, a collet member within the body also having a downturned marginal flange, and a fabric cover for the body member having marginal portions thereof gripped between the body and collet flanges, said collet having attaching prongs extending downward from the marginal flange thereof and having

10 a portion within the collet displaced downward substantially into the plane of the lower edge of the collet flange to provide a downwardly convex surface for coacting with the prongs.

6. In a button, in combination, a body member having a central opening and a downturned marginal flange, a collet having a body portion, a

15 downturned marginal flange and prongs extending downward from the flange, a fabric cover applied to the body member and having a marginal

20 portion thereof gripped between the inner margin of the body member and the body of the collet and an outer marginal portion gripped between the

25 downturned flanges of the body member and the collet.

7. In a button, in combination, a body member having a central opening and a downturned peripheral flange, and a collet fitting within the

30 body member and having an imperforate body portion disposed substantially in juxtaposed relation to the body member, a downturned marginal

35 flange fitting within the peripheral flange of the body member and prongs extending downward from the flange, and a piece of fabric covering the body and having the marginal portion thereof

40 gripped between the body and collet flanges.

8. In a button, in combination, a body member having a central opening and inner and outer

45 downturned flanges, a collet having a body portion received between said flanges, said collet

having a downturned marginal flange embraced by the outer flange of the body member and prongs extending downward from said collet

50 flange and adapted to be pressed inward and upward against the inner flange of the body member.

9. In a button, in combination, a body member having a central opening and inner and outer

55 downturned flanges, a collet having a body portion received between said flanges, said collet having a

60 downturned marginal flange embraced by the outer flange of the body member, and prongs extending downward from said collet flange and adapted to be pressed inward

65 and upward against the inner flange of the body member, and a fabric cover having marginal portions thereof extended around the inner and outer flanges of the body member and clamped between the body member and the collet.

10. In a button, in combination, a body member having a central opening therethrough and a

70 downturned marginal flange, a collet having a central boss extending upward through the opening of the body member, an annular downwardly

75 displaced portion surrounding the boss, a downturned flange fitting within the flange of the body member and prongs extending downward from the

80 collet flange and adapted to be pressed inward and upward against the inner flange of the body member, and a fabric cover having marginal portions thereof extended around the inner and outer flanges of the body member and clamped between the body member and the collet.

11. In a button, in combination, a body member having a central opening therethrough and a

85 downturned marginal flange, a collet having a central boss extending upward through the opening of the body member, an annular downwardly

90 displaced portion surrounding the boss, a downturned flange fitting within the flange of the body member, and prongs extending downward from the

95 collet flange and adapted to be pressed inward and upward against the inner flange of the body member, and a fabric cover having marginal portions thereof extended around the inner and outer flanges of the body member and clamped between the body member and the collet.

12. In a button, in combination, a body member having a central opening therethrough and a

100 downturned marginal flange, a collet having a central boss extending upward through the opening of the body member, an annular downwardly

105 displaced portion surrounding the boss, a downturned flange fitting within the flange of the body member, and prongs extending downward from the

110 collet flange and adapted to be pressed inward and upward against the inner flange of the body member, and a fabric cover having marginal portions thereof extended around the inner and outer flanges of the body member and clamped between the body member and the collet.

13. In a button, in combination, a body member having a central opening therethrough and a

115 downturned marginal flange, a collet having a central boss extending upward through the opening of the body member, an annular downwardly

120 displaced portion surrounding the boss, a downturned flange fitting within the flange of the body member, and prongs extending downward from the

125 collet flange and adapted to be pressed inward and upward against the inner flange of the body member, and a fabric cover having marginal portions thereof extended around the inner and outer flanges of the body member and clamped between the body member and the collet.
